Boys Blouse

8867

8867

UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A BOY'S BLOUSE.

SPECIFICATION forming part of Design No. 14,453, dated November 27, 1883.

Application filed September 26, 1883. Term of patent 3½ years.

To all whom it may concern:

Be it known that I, JOHN QUINCY REED, of the city, county, and State of New York, have invented and produced a new and original Design for a Pattern of a Boy's Blouse with Diagonal Front, (numbered 8,867;) and I do hereby declare that the engraved prints accompanying this specification convey to any one accustomed to using paper patterns a clear understanding of how a garment made up by the pattern will appear.

The design combines fronts that are shown closed diagonally from the right shoulder to the lower part of the left side, and a half-fitted

back displaying an under-folded box-plait at 15 lower end of the center seam, and also showing straps extending from the side seams, and a buckle situated over the center seam. Square pockets and coat-sleeves are added.

What I claim as my invention, and desire to 20 secure by Letters Patent, is--

The design for a boy's blouse with diagonal front, as shown in the engraved prints accompanying this specification.

JOHN QUINCY REED.

Witnesses:

ALFRED FRANCIS,
MARCELLUS CARLETON SHATTUCK.
